United States Patent Office.

EDWARD ROBERTS, OF PHILADELPHIA, PENNSYLVANIA.

Letters Patent No. 78,896, dated June 16, 1868.

IMPROVED APPARATUS FOR CUTTING THE TEETH OF WHEELS.

The Schedule referred to in these Letters Patent and making part of the same.

TO ALL WHOM IT MAY CONCERN:

Be it known that I, EDWARD ROBERTS, of the city of Philadelphia, in the State of Pennsylvania, have invented a new and useful Improvement in the Teeth-Cutting Engine; and I do hereby declare that the following is a full, clear, and exact description of the construction and operation of the same, reference being had to the accompanying drawings, making a part of this specification, in which—

Figure 1 is a perspective view, showing the improvement applied.

Figure 2, a horizontal section of the same, and

Figure 3 a side-view of one of the cutters—

Like letters of reference indicating the same parts when in the different figures.

My improvement relates more especially to the cutting of the tapering teeth in the spur-wheel which is operated by the worm-wheel in a gas-meter, and has for its object the cutting of such teeth with greater accuracy and facility than heretofore.

My invention consists in the arrangement of two cutting-disks parallel with each other, on the same rotary shaft, and equidistant from an imaginary straight line passing through the centre of the wheel which is to be cut, substantially as hereafter described and set forth.

Referring to the drawings, A A are the two cutters, B the rotary shaft, C the wheel as being cut, and D the base upon which the said wheel is supported.

The cutters A A are flat disks of tempered steel, each having serrated notches or cutting-teeth around its periphery, and a hole, a' in its centre, as represented in fig. 3.

The shaft B is made in the usual manner, having a fixed shoulder, b', and an adjustable screw-nut, b'', for securing the various-sized cutters thereon, as heretofore; but in addition to the adjustable nut b'', I apply a washer or stretcher, b''', between the shoulder b' and the nut b'', and thus provide for securing the two like cutters, A A, upon the said shaft, at the proper or intended distance apart. The length of the said stretcher b''' must be made to correspond with the intended distance apart, on the wheel C, of the furthest-apart sides of two contiguous teeth at their bases, and the shaft B supported to rotate in a horizontal position upon the points of two end-screws, (in the carrying-frame,) so that the said shaft can be adjusted endwise thereby, to suit the length of the particular stretcher used.

The "frame" which carries the shaft B is not shown in the drawings, because it is intended to be constructed and applied in the usual well-known manner, so that it can be readily moved up and down in front of the wheel C, whereby the rotary cutters are caused to pass across through the perimeter of the said wheel in cutting the teeth required; the shaft being rotated by a band, also applied in the usual manner.

The wheel C to be cut is fixed rigidly, by a screw-nut, upon the spindle of the usual index-plate, (not shown in the drawings,) so that it can be moved around by hand, in accordance with the number and distance apart of the teeth required in the said wheel.

In adjusting the positions of the two cutters A A upon the shaft B, (by means of the described shoulder b', stretcher b''', and nut b''), and the position of the shaft itself, longitudinally, (by means of the described supporting) and adjusting end-screws in the usual carrying-frame, the middle of the length of the stretcher b''' must be brought exactly in a straight line, passing horizontally through the centre of the wheel C, at right angles to the shaft B, as represented in connection with a dotted line in fig. 2, and consequently the two cutters A A will then be parallel to the said line and to each other, and also at equal distances from said line.

In the operation of the cutters A A upon the wheel to be toothed, C, it will be seen that on the first passage of the said cutters, two slots will be cut in the periphery of the said wheel, which will be parallel to each other, as seen in fig. 2; that if the wheel C be now rotated by moving the index-plate one space, and the cutters then again passed across through its periphery, two other like cuts, parallel to each other, will be made, the one cut being midway between the two first cuts, and the other an equal distance outside of one of them; that if the wheel C be then again rotated another notch of the index-plate, and the cutters A A again passed across through

the periphery of the wheel C, the rear cutter, in respect to the direction in which the slots are being cut around in the wheel C, will cut away one side boundary of the slot which it enters, and thus taper that side of the tooth, the other side of said tooth having already the proper taper given to it, in first cutting the slot parallel with the "radial line," and so on, operating in regular progression on the wheel C, one cutter making a straight slot, which gives the required taper to one side of a tooth to be made, and the other cutter tapering the side of slot, which is next to the previously-cut slot, until the whole of the required teeth have been cut and tapered, (see fig. 1.)

I am aware that tapering teeth can be cut at once by a single cutter, having bevelled side-cutting edges connected with serrated cutting-teeth on its periphery, but the liability of such cutter to break off the tooth which is being made, especially when the disk which is being toothed thereby is made of the hard metal required in the gas-meter wheels specified, has rendered it preferable, at the present time, to use a cutter without the bevel-teeth, its periphery only being serrated, so as to cut a straight slot with parallel boundaries, which are afterward widened by hand-filing, so as to give the required taper to the teeth.

I do not claim any of the devices herein described separately, for they are all old and well known; but

What I claim as new, and desire to secure by Letters Patent, is—

The combination of the spindle, collar, and clamping-nut, for supporting and clamping the wheel, with the device, consisting of the two cutter-disks, stretcher, tightening-nut, and adjustable shaft or arbor, all arranged substantially as described.

EDWARD ROBERTS.
